[57] CLAIM

The ornamental design for a carpenter level, as shown and described.

DESCRIPTION

FIG. 1 is a front elevational view of a carpenter level showing our new design;
FIG. 2 is a top plan view;
FIG. 3 is a bottom plan view;
FIG. 4 is a rear elevational view;
FIG. 5 is a right side elevational view;
FIG. 6 is a left side elevational view;
FIG. 7 is a front elevational view of an embodiment of FIGS. 1-6;
FIG. 8 is a top plan view;
FIG. 9 is a bottom plan view;
FIG. 10 is a rear elevational view;
FIG. 11 is a right side elevational view; and
FIG. 12 is a left side elevational view thereof.
